(57) **CLAIM**

The ornamental design for a skateboard chassis system with battery for a three-wheeler electric vehicle, as shown and described.

DESCRIPTION

FIG. 1 is a perspective elevation view of a skateboard chassis system with battery for a three-wheeler electric vehicle showing our new design;

FIG. 2 is a front view thereof;

FIG. 3 is a back view thereof;

FIG. 4 is top view thereof;

FIG. 5 is bottom view thereof;

FIG. 6 is a right-side view thereof; and,

FIG. 7 is a left-side view thereof.

The broken lines are for the purpose of illustrating portions of the article that form no part of the claimed design.

1 Claim, 7 Drawing Sheets
